Primary Examiner — Jeffrey D Asch*Assistant Examiner* — Rebekah A Caruso(74) *Attorney, Agent, or Firm* — NSIP Law(57) **CLAIM**

We claim the ornamental design for a mobile terminal, as shown and described.

DESCRIPTION

FIG. 1 is a top perspective view of a mobile terminal showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is a first perspective view thereof shown in a folded position; and,

FIG. 10 is a second perspective view thereof shown in a folded position.

The broken lines shown in the figures that are immediately adjacent to the shaded areas and define unshaded regions represent the bounds of the claim. The broken lines within

(Continued)

broken line boundaries are directed to environment. The broken lines form no part of the claimed design.

1 Claim, 8 Drawing Sheets
